DESIGN FOR AN ADJUSTABLE CURVE RULER

Peter Tom Tomasini, Sunnyside, N. Y.

Application September 27, 1943, Serial No. 111,214

Term of patent 14 years

To all whom it may concern:

Be it known that I, Peter Tom Tomasini, residing at Sunnyside, in the county of Queens and State of New York, have invented a new, original, and ornamental Design for an Adjustable Curve Ruler, of which the following is a specification, reference being had to the accompanying drawing, forming part thereof.

Figure 1 is a top plan view of an adjustable curve ruler showing my new design as it appears in use.

Figure 2 is a front edge elevational view of the longitudinal bar thereof.

Figure 3 is a transverse sectional view taken on line 3—3 of Figure 2.

Figure 4 is an end elevational view thereof.

The dominant features of my design are shown in solid lines on the drawing.

I claim:

The ornamental design for an adjustable curve ruler, as shown and described.

PETER TOM TOMASINI.
